Dorothy Goldberger, Chicago, Ill., assignor to Sol
Hammerman and Meyer Hammerman, both of Chicago, Ill.

Application July 27, 1944, Serial No. 114,574

Term of patent 14 years

(Cl. D3—17)

To all whom it may concern:

Be it known that I, Dorothy Goldberger, a citizen of the United States and resident of Chicago, in the county of Cook and State of Illinois, have invented a new, original, and ornamental Design for a Child's Playsuit or Similar Article, of which the following is a specification, reference being had to the accompanying drawing, forming a part thereof,

Fig. 1 is a front elevational view of a child's playsuit or similar article, showing my new design.

Fig. 2 is a rear elevational view thereof.

I claim:

The ornamental design for a child's playsuit or similar article, substantially as shown.

DOROTHY GOLDBERGER.
